UNITED STATES PATENT OFFICE.

PHILIP C. WENTWORTH, OF PROVIDENCE, RHODE ISLAND.

TWISTING TRAVELER.

1,415,072.

Specification of Letters Patent.

Patented May 9, 1922.

Application filed September 19, 1921. Serial No. 501,511.

To all whom it may concern:

Be it known that I, PHILIP C. WENTWORTH, a citizen of the United States, residing at Providence, county of Providence, 5 State of Rhode Island, have invented certain new and useful Improvements in Twisting Travelers, of which the following is a specification.

This invention relates to twisting travelers for use on vertical twisting rings. In ring twisting it is customary to lubricate the traveler by smearing the inner face of the twisting ring with a hard, non-fluid lubricating grease. With the ordinary vertical twisting traveler no provision is made for distributing this grease to the foot of the traveler which by reason of its frictional contact with the lower edge of the twister ring needs constant lubrication. In the operation of the ordinary traveler the following edge of the traveler body contacts the inner face of the ring and tends to dislodge the lubricant which falls through the ring and consequently does not reach the foot of the traveler where lubrication is most needed.

The object of my invention is to provide for a proper distribution of the lubricant to the foot of the traveler where the wear is greatest.

My invention is based on the action of the traveler during the run of the spindle and is a simple and effective solution of a problem which has long bothered textile engineers.

According to my invention the traveler itself is constructed to apply the lubricant to the traveler foot. To this end I provide the traveler with a lubricant catcher or collector which picks up and retains particles of the hard non-fluid lubricant from the inner face of the ring during the run of the traveler and as said lubricant melts under the heat developed between the traveler and the ring, directs the lubricant to the traveler foot. The traveler itself is therefore the agent by means of which the lubricant on the inner face of the twisting ring is redistributed and reapplied during the run of the traveler to the traveler foot.

The construction and operation of my traveler is described and illustrated in the accompanying specification and drawings and the characteristic features of novelty 55 are particularly pointed out in the appended claims. Throughout the specification

and drawings like reference characters are correspondingly employed, and in the drawings:

Fig. 1 is a view of a traveler in accordance with my invention in applied position upon a twisting ring.

Figs. 2 and 3 are a perspective and a section, respectively, showing one embodiment of my traveler.

Fig. 4 is a longitudinal section through the traveler shown in Fig. 1, and Fig. 5 is a face view of a further modification.

I have indicated at 1 a twisting traveler of standard type and at 2 a portion of a vertical twisting ring.

In Figs. 2 and 3 the outer or ring-contacting face of the traveler is longitudinally grooved between its ends as indicated at 3, and in Fig. 4, the traveler is slotted as indicated at 4.

During the run of the spindle the traveler frequently contacts the inner face of the ring, thereby mechanically transferring to itself particles of the lubricating grease with which the ring is smeared. As the traveler becomes heated, the grease thus transferred to it melts and is directed by the groove 3 or slot 4 downwardly towards the foot 5 of the traveler where the wear is greatest and the need of proper lubrication more pronounced. In my invention, therefore, the traveler itself is the agent for picking up or catching the lubricant with which the inner face of the ring is smeared and for redistributing and reapplying such lubricant particularly towards the foot of the traveler.

This distribution occurs while the traveler is running on the ring and is continuous. In the slotted form of traveler shown in Figs. 4 and 5, the slot or slots admit a draft of air from the spindle running within the ring through the traveler and this air current assists in forcing the lubricant outwardly and downwardly towards the foot of the traveler.

Various other modifications in the form and construction of my device may obviously be resorted to without departing from the spirit of my invention if within the limits of the appended claims.

What I therefore claim and desire to secure by Letters Patent is:

1. A twisting traveler for use on a vertical twisting ring and having a lubricant passage between its ends.

2. A twisting traveler for use on a vertical

2
twisting ring and having on its ring contacting face a lubricant passage.

3. A twisting traveler for use on a vertical twisting ring and having on its ring contacting face a longitudinally extending lubricant passage.

4. A twisting traveler for use on a vertical twisting ring and having on its ring contacting face a lubricant passage extending downwardly towards the foot of the traveler.

5. A twisting traveler for use on a vertical twisting ring and having on its ring contacting face a longitudinally extending lubricant passage terminating short of the foot of the traveler.

6. A twisting traveler for use on a vertical twisting ring, formed to mechanically transfer to itself lubricant from the ring and to direct such lubricant toward the traveler foot.

7. A twisting traveler for use on a vertical twisting ring, formed between its edges to mechanically transfer to itself lubricant from the ring and to direct such lubricant toward the traveler foot.

8. A twisting traveler for use on a vertical twisting ring, having means effective to mechanically transfer to the traveler lubricant from the ring and to direct such lubricant toward the traveler foot.

9. A twisting traveler for use on a vertical twisting ring, having a lubricant collecting area effective to mechanically transfer to the traveler lubricant from the ring and to direct such lubricant toward the traveler foot.

10. A twisting traveler for use on a vertical twisting ring, having a lubricant collecting area between its edges effective to mechanically transfer to the traveler lubricant 40 from the ring and to direct such lubricant toward the traveler foot.

11. A traveler for use on a vertical twisting ring, having a lubricant catcher effective to pick up lubricant from the inner face of 45 the ring and to direct such lubricant towards the foot of the traveler.

12. A traveler for use on a vertical twisting ring, having a lubricant catcher between its lateral edges effective to pick up lubricant 50 from the inner face of the ring and to direct such lubricant towards the foot of the traveler.

13. A twister traveler for use on a vertical twisting ring, comprising a body portion 55 having a slot opposite the inner face of the ring and effective to pick up lubricant from the ring and to direct such lubricant toward the foot of the traveler.

14. A twister traveler for use on a vertical 60 twisting ring comprising a body portion having a longitudinally extending slot opposite the inner face of the ring and effective to pick up lubricant from the ring and to direct such lubricant toward the foot of the 65 traveler.

In testimony whereof I affix my signature in presence of two witnesses.

PHILIP C. WENTWORTH.
